UNITED STATES PATENT OFFICE.

ADOLPH G. KUPETZ, OF NEW ROCHELLE, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed October 20, 1922. Serial No. 595,766.

This invention relates to typewriting machines, and more particularly to typewriting machines especially adapted for the writing of bills for telephone service, in which operation it is required to type separately the amounts of United States taxes. The invention, however, is useful with or without modifications for other purposes.

It is desired not only to type the tax items 10 separately, but also to ascertain the total of the tax items for a day or other period. In machines designed for this purpose, there are provided, in addition to the usual number-keys, a special key to type the number "5" and another special key to type the number "10." These two special keys are used for no other purpose, and each is operatively connected to a register, such as the well-known Veeder cyclometer. These 20 registers count the operations of their respective keys, and thus enable the operator to determine the total of the tax items by a very simple calculation.

A feature of the invention is the provision 25 of improved means for attaching the register mechanism and its operating connections to a standard typewriter without drilling holes or making any other alterations whatever in the machine frame.

30 In my application No. 592,682, filed October 6, 1922, now Patent No. 1,559,889, dated November 3, 1925, I have disclosed registers for the purpose above indicated, wherein register-operating arms are 35 yieldingly operated and are maintained at the ends of their operating strokes by springs, and are moved preparatory to their operation by the springs by operating connections between them and the special keys.

40 By this arrangement, the danger of damage to the register mechanism is obviated, lost-motion is provided between the number-keys and the register mechanism in the last portions of the downward movements of the 45 number-keys, and the number-wheels of the registers are normally maintained in a locked condition to prevent persons from carelessly or ignorantly turning the clearing shaft, and thereby altering the positions of the 50 wheels. The present invention aims to preserve these desirable features, while simplifying the connections whereby they are

achieved, and adapting said connections for attachment to a standard machine without alteration thereof.

55 In my application No. 592,682, previously referred to, the registering elements are positively connected to the key-lever, and a quick return movement of the key-lever must necessarily force the driving 60 and carry-over elements of the register to perform their several functions during an interval of time that is almost instantaneous, with the result that errors may develop because of defective co-operation between the 65 registering parts, due to the speed of operation. In my present organization it will be particularly noted that the numeral-key has no positive connection to the register. The numeral-key overlies a register-actuating 70 arm in such a manner that the down-stroke of the key will vibrate the actuator in unison to the end of the key's down-stroke, to condition the register-driving elements, and upon the release of the key by the finger 75 the key-lever is free to return independently of the register-actuating arm. This enables the key-lever to be restored under its normal predetermined spring-tension, free of any extra register-operating burden that 80 might tend to slow down or impede the return movement of its associated type-bar. It also enables the actuating spring of the register that becomes active upon the release of the key-lever to be tensioned very 85 lightly for the light duty it performs, makes the restoring interval for the actuator arm of longer duration, effectively removes any possibility of injurious strain to the light toothed elements of the register, and 90 incidentally prevents errors during the registering movements. The numeral register keys are never struck twice in succession, hence the slower returning movement of the register actuator will not delay or 95 retard the typing operations immediately following a registering movement.

As in the application referred to above, it is desirable to arrest the rotation 100 of the clearing shaft with the number-wheels standing at "9," in order that the adding in of a unit, which necessarily follows the turning of the clearing shaft, will restore all the number-wheels to "0." A

feature of the present invention is the provision of improved means for clearing the register, comprising a stop for positively arresting the rotation of the shaft with the 5 wheels standing at "9."

Other features and advantages will hereinafter appear.

In the accompanying drawings,

Figure 1 is a front elevation, partly in 10 section, of the right end of a typewriting machine, with the improvements of the present invention applied thereto.

Figure 2 is a side elevation of the mechanism shown in Figure 1, with the register 15 clearing handle in its normal position.

Figure 3 is a vertical section of the register on the line 3—3 of Figure 1.

Figure 4 is a vertical section of the register on the line 4—4 of Figure 1.

Figure 5 is a view similar to Figure 2, 20 showing the clearing handle in the position to which it is moved to bring the number-wheels to "9."

Figure 6 is a vertical sectional view of the 25 register, showing the clearing handle in normal position, and a spring for returning it to normal position.

The typewriting machine comprises the usual keys 11, which, through connections 30 to type-bars 12, cause them to strike rearwardly against a platen mounted upon a carriage (not shown). In addition to the usual number-keys and the usual alphabet-keys, there is provided one or more special 35 number-keys 5. Only one such key and only one register 13 are shown, but it will be readily apparent, of course, that the principle of the invention is not confined to the provision of a single special key and register. 40

The machine frame 14, as usual, has a triangular opening 15 at the right end of its keyboard extension. A bracket 16 and a clamping plate 17 lie on the opposite sides 45 of the frame and are connected to each other by three binding screws 18, which screws are received in holes in the bracket and clamping plate, so arranged that the screws 18 will lie adjacent the vertices of the triangular 50 opening 15 in the machine frame 14 and cause the bracket 16 and clamping plate 17 to clamp the frame firmly. The clamping plate may be positioned by engagement of 55 its upper edge 21 with a shoulder 22 on the machine frame. The lower portion of the bracket is provided with a bushing 23, in which is journaled a rock-shaft 24, bearing at its inner and outer ends, respectively, 60 crank-arms 25 and 26. The crank-arm 25 is curved upwardly, and has a headed stud 27 near its outer extremity arranged to underlie and be engaged by the stem 28 of the special number-key 5, the operations of which are to be counted. The arm 26 is 65 justably fixed on the shaft 24 by means of a

set screw 26^a. The upper end of the arm 26 has a slot 29 which receives a pin 30 on an operating arm 31 of the register 13. The register 13 is mounted on a shelf portion 32 of the bracket 16. The forward end of the 70 operating arm 31 is normally maintained in an elevated position by a tension spring 33 connected to the tail 34 of the operating arm 31 and to the bracket 16. Depression of the special key 5 rocks the operating arm 31, 75 by means of the described connections, from the position of Figure 2 to the position of Figure 5.

The operating arm 31 is connected to and oscillates a yoke 35, upon which is pivot-

ally mounted a series of pawls 36, which pawls are pressed toward number-wheels 37 of the register by a spring 38 and co-oper-

ate with ratchet teeth 39 and intervening shallow and deep notches 40 and 41 on the 80 number-wheels. The hub portion 42 of the yoke 35 is connected through gear teeth to a segment 43, which it oscillates to carry

stops 44 into and out of the path of the ratchet teeth 39 on the number-wheels 37. 85 Return locking pawls 45 prevent retrograde movement of the number-wheels. A regis-

ter-clearing shaft 46 has a series of one-toothed disks 47 keyed to it, one for each 90 number-wheel of the register, and each num-

ber-wheel is provided with a pawl 48 and a spring 49 for pressing the pawl into en-

gagement with its disk 47. When the clearing shaft 46 is rotated clockwise, as seen in 95 Figure 3, the disk-teeth 50 pick up the num-

ber-wheel pawls 48 in the positions to which 100 they have been moved by the operating pawls 36 and turn the number-wheels for-

ward. The register mechanism described is 105 the usual mechanism of the Veeder cyclometer.

The number-wheel-operating mechanism, 110 however, is normally maintained in the position shown in Figure 3, that is, in the position occupied at the conclusion of the ad-

vance or operating stroke of the register-operating arm 31. It will be noticed that 115 the number-wheels are locked against ad-

vance in Figure 3 by the stops 44. In order 120 to permit turning of the wheels by the clear-

ing shaft 46, therefore, it is necessary for 125 the operating arm 31 of the register to be de-

pressed, which, of course, will result in a unit being run into the number-wheels of 130 the register upon the restoration of the oper-

ating arm to normal position immediately 135 after the operation of the register-clearing shaft has been completed. A register-clear-

ing handle 51 is rotatably mounted on the 140 register-clearing shaft 46 and carries a pawl 52, which is spring-pressed into engagement

with a toothed wheel 53 fixed to the shaft, 145 whereby a one-way driving connection is estab-

lished between the handle and shaft. A stop 54 is mounted to lie in the path of 150

the clearing handle and positively arrest turning of the handle 51 with the number-wheels standing at "9". A spring 55 returns the handle independently of the clearing shaft to its normal position, which is the position occupied by it in Figure 2. The stop 54 also limits this return movement of the handle. The operating arm 31 of the register is then permitted to rise, 10 which runs in a unit and thereby turns all the wheels to "0".

The clearing shaft 46 is turned through only nine-tenths of a revolution by the clearing handle 51. In order to bring the tooth 56 on the wheel 53 again into operative relationship to the pawl, the revolution of the shaft 46 must be completed. A cam 57 having an inclined surface 58 thereon, which terminates in a deep notch 59, is keyed to the clearing shaft 46, and a detent 60 is pressed by a spring 61 against said cam 57. When the wheels 37 are brought to the "9" position by the clearing shaft, the detent 60 presses against the inclined surface 58 of the cam 57 on the clearing shaft. The pressure of the spring 61 is not sufficient to cause rotation of the clearing shaft 46 so long as the number-wheels remain in driven relationship thereto, but as soon as 20 the number-wheels have been turned to "0" by the running in of a unit, the spring 61 is effective through pressure of the detent 60 upon the inclined surface 58 of the cam 57 to rotate the clearing shaft forward and thereby bring the tooth 56 on the wheel 53 into position to be engaged and driven by the pawl 52 on the register-clearing handle.

Variations may be restored to within the scope of the invention, and portions of the 40 improvements may be used without others.

Having thus described my invention, I claim:

1. In a typewriting machine including a full complement of alphabet and numeral 45 keys for typing, an extra key, a register for counting the operations of the extra key, manually-operable register-clearing means to partially clear the register, and means released by the extra key to complete the 50 register-clearing operation.

2. In a typewriting machine including a full complement of alphabet and numeral keys for typing, an extra key, a register for counting the operations of the extra key, 55 manually-operable register-clearing means rotatable between fixed stops to partially clear the register, and means released by the extra key to complete the register-clearing operation.

60 3. In a typewriting machine including a full complement of alphabet and numeral keys for typing, an extra key, a register for counting the operations of the extra key, a manually-operable self-restoring crank- 65 arm rotatable between fixed stops to par-

tially clear the register, and means released by the extra key to complete the register-clearing operation.

4. In a typewriting machine including a full complement of alphabet and numeral 70 keys for typing, an extra key, a register for counting the operations of the extra key, and register-clearing means including a manual means to initially condition the register for a final clearing movement by 75 means released by the extra key.

5. In a typewriting machine, a number-key, and a register for counting the operations of the number-key, comprising number-wheels, means for advancing the number-wheels in counting, a clearing shaft, means mounted on the clearing shaft for turning the clearing shaft, a stop for positively arresting the rotation of the turning means before it has made a complete revolution, a spring for returning the turning means to initial position independently of the shaft, and means for further turning the shaft to complete a revolution thereof and thereby restore it to its operative relation 90 with its turning means.

6. In a typewriting machine, a number-key, counting mechanism comprising number-wheels, an operating arm, means controlled by the number-key for oscillating 95 said arm to operate the counting mechanism, comprising a spring for moving the arm in its operative direction and maintaining it normally at the end of its operating stroke, locking means controlled by the operating arm for normally locking the counting mechanism and arranged to unlock the counting mechanism when the operating arm is moved in an idle direction to prepare the counting mechanism for counting, a clearing 100 shaft for turning the number-wheels, means for turning the shaft, a stop for positively arresting the shaft-turning means with the number-wheels standing at "9", a spring for returning the shaft-turning means to initial 110 position, and means for further advancing the clearing shaft upon the return of the operating arm to normal position.

7. In a register, a set of number-wheels, a clearing shaft for turning the number-wheels, a toothed wheel fixed to the clearing shaft and having a tooth thereon, a handle, a pawl carrier by the handle in engagement with the tooth of the wheel for turning the clearing shaft, a stop for positively arresting the handle with the number-wheels standing at "9", means for returning the handle to initial position independently of the shaft, means for advancing the number-wheels in unison to "0", and means for advancing the clearing shaft to turn the tooth on the toothed wheel into operative relationship to the pawl on the handle when the number-wheels are turned to "0".

8. In a register, a set of number-wheels,

- a clearing shaft for turning the number-wheels, means for turning the shaft in clearing the register, a stop for positively arresting the turning of the shaft-turning means with the number-wheels standing at "9", and means for restoring the shaft and shaft-turning means to their initial positions in co-operative relationship to each other by rotation in opposite directions.
- 10 9. In a register, a set of number-wheels, a clearing shaft for turning the number-wheels through part of a revolution, means for turning the clearing shaft, a stop for positively arresting the turning means when a revolution has been partially completed, means for returning the shaft-turning means to initial position, and means for causing the number-wheels and the clearing shaft to complete a revolution.
- 15 10. In a register, a set of number-wheels, a clearing shaft for turning the number-wheels through part of a revolution, means for turning the clearing shaft, a stop for positively arresting the turning means with the number-wheels standing at "9", means
- for returning the shaft-turning means to initial position, a lock for normally locking the number-wheels against turning movement by the shaft, an arm movable to an abnormal position to unlock the number-wheels and effective in its return to normal position to cause a unit to be run into the number-wheels, and means for causing the clearing shaft to complete a revolution.
- 20 11. In a register, a set of number-wheels, an operating arm for operating the number-wheels to count, normally maintained at the end of its operating stroke and effective in that position to lock the register, said operating arm being movable to an abnormal position to unlock the register, means for turning the number-wheels in clearing the register, means for positively arresting the movement of the turning means with the number-wheels standing at "9", and a spring for automatically returning the operating arm to normal position to cause the number-wheels to be advanced to "0".

ADOLPH G. KUPETZ.
